UNITED STATES PATENT OFFICE.

MARION M. COX, OF CORONA, NEW MEXICO.

ROD-CLAMP.

1,138,195.

Specification of Letters Patent.

Patented May 4, 1915.

Application filed May 10, 1913. Serial No. 766,778.

To all whom it may concern:

Be it known that I, MARION M. COX, a citizen of the United States, residing at Corona, in the county of Lincoln and State 5 of New Mexico, have invented new and useful Improvements in Rod-Clamps, of which the following is a specification.

This invention relates to improvements in pipe and rod clamps or grips and has particular application to an automatic clamp or grip.

In carrying out the present invention, it is my purpose to provide a grip or clamp whereby, in the drawing or raising of the 15 tubes or rods of artesian or oil well pumps, such tubes or rods will be effectively grasped and held in the desired elevated position so that a fresh grip may be obtained upon the tube or rod to complete the drawing or 20 pulling thereof.

It is also my purpose to provide a tube or rod grip of the class described which will embrace the desired features of simplicity, efficiency, durability and strength coupled 25 with cheapness of cost in manufacture and marketing and which may be readily applied to a pipe or rod.

With the above and other objects in view, the invention consists in the construction, 30 combination and arrangement of parts hereinafter set forth in and falling within the scope of the claim.

In the accompanying drawing: Figure 1 is a plan view of a grip constructed in accordance with the present invention, the same being shown as applied to a tube. Fig. 2 is a transverse sectional view through the grip, the tube being shown in elevation. Fig. 3 is a perspective view of one of the 40 jaws.

Referring now to the accompanying drawing in detail, A designates the pump rod of an Artesian or oil well pump, while B indicates my improved clamp or grip as an entirety, such grip comprising a ring-like member formed of two sections 1, 1 pivotally connected to one another through the medium of a pivot pin 2 and having the free end extended outwardly as at 3 and 45 formed with alining apertures 4 through which is passed a headed bolt 5, having threadedly engaging the free end thereof of a clamping nut 6. These sections 1, 1 constituting the ring-like member are, when the 50 grip is put into service, designed to encircle the rod or tube of the pump, as illustrated

in the drawing and have the inner concaved edges thereof suitably spaced apart from the rod.

The numerals 7, 7 designate jaws each composed of a flat piece of metal having one edge concaved as at 8 and toothed or serrated as at 9. Extending outwardly from the opposite ends of each jaw 7 adjacent to the remaining edge thereof are pintles 10, 10 designed to engage eye bolts 11 carried upon one side of one of the sections 1 of the ring-like member. It will be observed that the jaws 7, 7 are disposed at diametrically opposite points so as to grip the rod or 70 pipe in an even and uniform manner.

From the foregoing description taken in connection with the accompanying drawing, the construction, mode of operation and manner of employing my invention will be 75 readily apparent. When it is desired to draw or elevate the pump rod or tube, the sections of the ring-like member are swung about their pivot end so as to open the grip and enable the latter to be applied to the 80 rod. The sections are now drawn together through the medium of the bolt 5 and clamping nut 6 and the serrated edges of the jaws 7, 7 grip the rod, the jaws being disposed at an inclination, incident to the 85 distance between the inner wall of the ring-like member and the rod, as clearly illustrated in Fig. 2. As the pipe or tube is drawn upwardly or elevated, such pipe or tube is relieved of the influence of the jaws, 90 while when the tube is released a fresh grip may be obtained thereon to complete the hoisting, the jaws will automatically grasp the tube and so prevent the latter from downward movement.

The teeth 9 on each jaw are formed into two rows, the teeth of each row being staggered relatively and inclined reversely to those of the adjacent row so that the jaws will effectively grip the pipe or rod. 95

It will be noted that by having the apices of the teeth working in different radii there is a neutral position where the apices of the two rows of teeth grip the rod simultaneously. The apices of one row of teeth 100 are active on one side of this neutral position while the apices of the second row are active on the opposite side. One side of the teeth of one row is flush with one side of the jaw while one side of the other row 105 of teeth is flush with the opposite side of the jaw.

I claim:

A grip of the class described comprising a pair of concaved jaws movable toward and away from each other and having two 5 rows of staggered and reversely inclined teeth formed on the confronting edges, one side of the teeth of one row being flush with one side of the jaw, one side of the teeth of the other row being flush with the opposite 10 side of the jaw, the said rows of teeth hav-

ing their respective apices operating in arcs of different radii and active on relatively opposite sides of a neutral position respectively.

In testimony whereof I affix my signature in presence of two witnesses:

MARION M. COX.

Witnesses:

J. W. PARKER,
A. W. VARNEY.
